UNITED STATES PATENT OFFICE

JAMES B. FISHER, OF WAUKESHA, WISCONSIN, ASSIGNOR TO WAUKESHA MOTOR COMPANY, OF WAUKESHA, WISCONSIN, A CORPORATION OF WISCONSIN

CRANK-CASE CONSTRUCTION

Application filed April 20, 1927. Serial No. 185,141.

This invention relates to crank case construction and covers particularly an improved and more practical structure for more rigidly supporting the main crank shaft bearings and for strengthening and stiffening the crank case against flexure and distortion.

The inertia load on the main bearings in a crank case when the engine is running causes inner stresses and strains in the crank case structure. This is particularly true in crank case construction in which the side walls drop below the shaft center and in such structure there is a bending action in the case and a spreading and contracting tendency of the lower edges of the case. Such spreading and contraction could be offset and prevented by a truss or chord member across the bottom of the case connecting the two edges, but such structure would be complicated and impractical on account of the resulting inaccessibility.

The important object of this invention is to overcome the spreading and contracting tendency of the lower edges of the crank case by providing truss structures for supporting the main bearings for the crank shaft. Each truss structure comprises upper and lower arch members extending between the side walls of the crank case and connected by a web, the lower arch members directly supporting the bearings structure.

Another object of the invention is to provide box beam structures along the outside of the crank case side walls at the bottom thereof and to so arrange the beam structures that their walls will cooperate with the arch members to form rigid truss structures for supporting the various bearings, said beam structures serving also to stiffen and brace the crank case against flexure and distortion.

Referring to the drawings,

Figure 1 is a plan view of a crank case with parts broken away;

Fig. 2 is a sectional view on plane 2-2 of Fig. 1;

Fig. 3 is a sectional view on plane 3-3 of Fig. 1; and

Fig. 4 is a sectional view on plane 4-4 of Fig. 2.

The crank case shown is for a 6-cylinder en-

gine and comprises the side walls 10 and 11 and a top wall 12, in which top wall are the openings 13 over which the cylinder structures are mounted.

For supporting the main bearing structures B for the crank shaft I provide, in accordance with my invention, the truss structures T. Each truss structure comprises the upper and lower arch members 14 and 15 extending between the side walls 10 and 11 of the crank case, the lower arch member containing the upper bearing member b, and between the upper and lower arch members and the upper bearing extends the vertical web part 16. The entire truss structures are preferably an integral part of the crank case casting. The arch members are, as shown, of flat rectangular cross section so that the truss structure is of I-beam cross section.

In practice the engine crank shaft (not shown) is journaled between the upper and lower members b and b' of the bearing structures and during inertia load on the bearings the arch members 15 are subjected alternately to heavy compression and tension, the compression tending to spread the arch members and the sides of the crank case while the tension will tend to draw the arch member ends and the crank case walls toward each other, the result being that breakage and cracks may form at the weakest point which will probably be at the corners c at the ends of the upper bearing members b unless the bearing supporting arch members were sufficiently strengthened.

By providing the truss arrangement described the bearing supporting arch members will be sufficiently strengthened and reinforced so that breakage or cracking will be entirely prevented. The crank shaft or bearing load will be transferred in part to the upper arch member b to the web 16.

The weight of the crank shaft structure and bearing structures and the down thrust of the pistons will be transmitted through the arch members to the side frame sections 10' and 11' and to the frame 17 on which the crank case is mounted.

To strengthen and stiffen the crank case against bending or sagging I provide the hollow or box beam structures D along the out-

side of the wall sections 10' and 11' and have preferably shaped these beam structures so that their upper walls 18 form a continuation of the upper arch members 14 of the truss structures. The lower walls 19 of the beam structures will then extend between the ends of the arch members and form extended foot or seating surfaces therefor besides holding the arch members against spreading at their ends. The arrangement will materially stiffen and strengthen the truss structures and increase their supporting capacity and rigidity. In other words, the beam structures 15 will act as braces for resisting longitudinal expansion and contraction of the truss structures. With such strong and rigid truss structures chord members between the truss ends are entirely unnecessary and the space below the bearings and truss structures can be kept entirely clear for ready accessibility.

At the ends of the crank case the end walls 20 extend between the tops of the end truss structures and the top wall 12. At the intermediate truss structures the space above them may be kept entirely clear to permit greater accessibility to the crank case and the operating parts therein.

Bearing boxes 21 may be secured on or cast integral with the truss structures for 25 journaling the engine cam shaft, and above the line of the cam shaft are provided the enclosures or chambers 22 into which extend the valve stems and valve tappets (not shown) for cooperating with the cam shaft, these chambers 22 being accessible through hand holes 23 in the side walls of the crank case.

I thus produce a strong and rigid crank case structure which may be in the form of a single casting and which is comparatively light, and which incorporates truss structures for supporting and maintaining the crank shaft in accurate alignment and for preventing distortion or bending of the crank case as a whole or of its walls.

45 I claim as follows:—

1. A crank case structure comprising side walls, truss structures between said walls each comprising upper and lower upwardly curved arch members and a web member, crank shaft bearing structures supported on said truss structures, a wall extending outwardly from each of said side walls and aligned with and forming a continuation of the upper arch members of said truss structures, and bottom walls extending between the lower ends of said side walls and said extension walls.

50 2. A crank structure in the form of an integral casting comprising side walls, sets of upper and lower upwardly arched arch members and intervening web members extending between said side walls to form truss structures, diagonally extending walls outside of said side walls and aligned with and

forming continuations of the upper arch members of said truss structures, horizontal walls extending between said diagonally extending walls and the lower ends of said side walls, and bearing supporting frames interposed in said truss structures above the lower ends of said side walls.

55 3. A crank case structure comprising side walls and a top wall, truss structures of I-beam construction connecting the side walls and each arched upwardly as a whole, and hollow beams of approximately triangular cross-section extending along the sides of the crank case, the upper walls of said beams being aligned with and constituting continuations of the upper elements of the truss structures.

60 4. A crank case structure comprising side walls and a top wall, truss structures of I-beam construction connecting the side walls and each arched upwardly as a whole, and hollow beams of approximately triangular cross-section extending along the sides of the crank case, the upper walls of said beams being aligned with and constituting continuations of the upper elements of the truss structures, the lower walls of the beams being substantially horizontal and the lower elements of the truss structures terminating at the inner edges of said lower walls.

65 In witness whereof, I have hereunto set my hand this 7 day of April, 1927.

JAMES B. FISHER.
